UNITED STATES PATENT OFFICE.

WILLIAM L. LUKENS, OF BETHLEHEM, PENNSYLVANIA, ASSIGNOR TO BETHLEHEM STEEL COMPANY, A CORPORATION OF PENNSYLVANIA.

FUSE FOR PROJECTILES.

Application filed April 7, 1923. Serial No. 630,486.

To all whom it may concern:

Be it known that I, WILLIAM L. LUKENS, a citizen of the United States, and residing at Bethlehem, Northampton County, State of Pennsylvania, have invented certain new and useful Improvements in Fuses for Projectiles, of which the following is a specification.

This invention relates to artillery ammunition and particularly to projectiles having point detonating fuses of the adjustable type.

In the application filed September 20, 1922, in the names of William L. Lukens and John A. Taylor, Serial No. 589,434, is disclosed and claimed a projectile within the walls of which is secured a fuse of the adjustable type which is adapted to be adjusted from without the projectile by means extending through an aperture in the projectile wall to give different speeds of action. The fuse disclosed is of novel form and is adapted to be adjusted to effect the detonation of the projectile bursting charge either before the projectile body strikes the target at the instant the projectile body strikes the body or after the projectile body strikes the target. The means for causing the fuse to function before the projectile body contacts with the target comprises an anticipator insertable through the aperture in the projectile wall and projecting in front of the projectile, the inner end of the anticipator being connected to a movable part of the fuse, that is, to a firing pin carrier which is thrust rearwardly when the end of the anticipator strikes the target to contact with the primer.

The object of the present invention is to improve on the invention disclosed in the application above mentioned whereby the fuse is rendered simpler in construction and cheaper to manufacture and the projectile with which it is used safer to handle and to fire from a gun. In the present fuse all possibility of premature explosion in the gun barrel when the anticipator is used is avoided, the present construction being such that the anticipator is connected to a non-movable portion of the fuse.

The invention may be embodied in various forms, one of which is illustrated in the accompanying drawings by way of example.

In the drawings:

Figure 1 is an axial longitudinal section

through the forward portion of an explosive projectile having the novel fuse and fuse adjusting means incorporated therein, the fuse being adjusted for delayed action and the parts being shown in the positions which they occupy before the projectile is fired from a gun;

Figure 2 is a similar view showing the positions of the parts after the projectile has struck a target;

Figure 3 is a view similar to Figure 1 but showing the positions of the parts of the fuse after striking a target where the fuse has been adjusted previously before firing to give immediate detonation instead of a delayed detonation;

Figure 4 is a view similar to Figure 3 showing the positions of the fuse parts after striking a target where the anticipator pin is used;

Figure 5 is a section on the line 5—5 of Figure 2; and

Figure 6 is a section on the line 6—6 of Figure 1.

A hollow projectile body is indicated at 10 and its ogival nose is shown at 11, the adjacent ends of these portions having threaded engagement with the internally and externally threaded adapter 12. The adapter 12 supports the fuse F, the cylindrical rear portion of the head 13 of the fuse having threaded engagement with the inner wall of the adapter. The body portion 14 of the fuse is of less diameter than the head and extends into and has threaded engagement with the axial recess in the head.

The ogival point 11 of the projectile is provided with a circular axial aperture in its forward end and a plug 15 extends into this aperture, this plug being provided with retaining springs 16 which engage in recesses 17 so that the plug is held frictionally in position, but may be removed manually from the aperture in which it normally rests. The body portion of the fuse is formed substantially in the manner described and claimed in Patent No. 1,250,919 issued to J. P. Madden and W. L. Lukens, December 18, 1917.

The head of the fuse is substantially cylindrical though tapering externally at its extreme forward end so as to clear the inner wall of the point 11. The axial opening in the head is also substantially cylindrical

although having three sections of different diameter, the front section having the smallest diameter. As before stated, the forward end of the fuse body 14 has threaded engagement with the wall of the axial recess in the head of the fuse. Positioned between the oppositely facing shoulders of the head and body of the fuse are abutting disks 19 and 20, each of which is centrally 10 apertured so that a continuous flame passage through the disks is provided. The disk 19 has threaded engagement with the body 14 of the fuse and serves to retain within the body the centrifugal cage 21, and 15 the plunger 22, these members being positioned in communicating coaxial chambers in the fuse body, and functioning in the manner pointed out in the prior patent referred to. The disk 20 serves to retain within 20 the recess in the head of the fuse the movable parts therein contained, when the head is detached from the base or body.

A firing pin carrier is indicated at 23 having secured thereto a firing pin 24, said 25 carrier fitting within the forward section of the axial aperture in the head of the fuse and having threaded engagement therewith so as to be non-movable relatively to the fuse head after the parts have been assembled. Slidably contained within the 30 cylindrical axial aperture in the fuse head is the primer carrying block or cylinder 25. Normally, this block is prevented from approaching the firing pin by means of the 35 centrifugal locking bolts 26 which are urged inwardly by springs 27. A creep spring 28 is also interposed between the slidable primer carrier and the stationary firing pin carrying block 23 which opposes movement 40 of the primer carrier toward the firing pin. The primer is indicated at 29, a flash port bolt at 30 and flash powder at 31 and 32.

An enlarged section of the primer carrier is shown in Figure 6 and it will be seen 45 from this drawing that the aperture 35 in the flash port bolt, which is shown in the position which it normally occupies, is in communication with a chamber containing a delay pellet 36 which chamber in turn 50 communicates by means of an aperture 37 with the flash powder 32. A spring 39 normally tends to move the flash port bolt 30 to such position that the port or conduit 40 in this bolt provides a direct flame passage 55 between the flash powder 31 and flash powder 32, as shown in Figures 3 and 4. Normally, however, the flash port bolt is locked against movement by a cotter pin 41 which 60 extends through apertures in the primer carrier and flash port bolt and which is connected by means of a cord 42 to the plug 15. When the cotter pin 41 has been withdrawn, which may be accomplished by 65 pulling out the plug, the flash port bolt will move to the position in which it is shown

in Figure 3 so that ignition of the primer will result in immediate ignition of the flash powder 31 and 32 and hence the detonating charge of the fuse.

When it is desired to bring about the explosion of the projectile before the nose has struck the target the plug 15 and the cotter pin 41 are completely withdrawn and the anticipator pin 43 inserted through the aperture in the point. This anticipator has a recess in its end adapted to receive a boss 44 projecting axially forward from the threaded plug 23 which constitutes in reality the forward end of the fuse. The retaining spring 45 on the boss engages within apertures in the pin to hold the same frictionally in position. If the projectile armed with the anticipator has normal impact with the target the progress of the projectile is arrested before the projectile body contacts with the target and the primer carrier moves forward so that the primer contacts with the firing pin, as shown in Figure 4, and the projectile is exploded before the nose proper has struck the target. If the projectile strikes the target a glancing blow so that the end of the anticipator does not contact with the target, the fuse will function nevertheless by the forward movement of the primer carrier.

To one skilled in the art the advantages and possibilities of the invention will be apparent and it will also be obvious that the design and arrangement of the component parts of the fuse may be changed without departing from the spirit of the invention.

Having thus described the invention what is claimed as new and desired to be secured by Letters Patent is:

1. The combination with a hollow projectile body having an aperture therein, of a fuse completely enclosed within the projectile wall and adapted to be adjusted for different speeds of action, means for controlling the adjustment of the fuse and removable through said aperture, and an anticipator insertable through said aperture after the removal of said means, said fuse and anticipator having interengaging means whereby the latter may be detachably secured to a fixed portion of the fuse.

2. The combination with a hollow projectile body having an aperture therein, of a fuse enclosed within the projectile wall and secured thereto, said fuse having a non-movable portion at its forward end and being adjustable for different speeds of action, said non-movable portion having means thereon for the attachment of an anticipator insertable through the aperture in the projectile body.

3. The combination with a hollow projectile body having an aperture therein, of a fuse enclosed within the projectile wall

and secured thereto, said fuse being adjustable for different speeds of action, and said fuse having a non-movable portion at its forward end against which an anticipator 5 introduced through said aperture may rest.

4. The combination with a hollow projectile body having an aperture therein, of a fuse completely enclosed within the projectile wall and adapted to be adjusted for 10 different speeds of action, means for controlling the adjustment of the fuse and removable through said aperture, a detachable plug closing said aperture, a link connection between said means and said plug, and 15 an anticipator insertable through said aperture after the removal of said plug, said fuse and anticipator having interengaging means, whereby the latter may be detachably secured to a fixed portion of the fuse.

20 5. In a fuse for projectiles, the combination with a fuse body, of an anticipator

adapted to be secured to the fuse body, a boss projecting axially forward from said body and fixed thereto, said anticipator having a recess formed in the end thereof receptive of said boss, and a spring member 25 fixed to said boss and adapted to frictionally engage the anticipator.

6. In a fuse for projectiles, the combination with a fuse body, of an anticipator 30 adapted to be secured to the fuse body, a member projecting axially forward from said body and fixed thereto, said anticipator having a recess formed in the end thereof receptive of said member, and resilient 35 means fixed to said member and adapted to detachably secure the anticipator to the fuse body.

In testimony whereof I hereunto affix my signature.

WILLIAM L. LUKENS.
